UNITED STATES PATENT OFFICE.

ARTHUR H. NOBLE, OF PAWTUCKET, RHODE ISLAND, ASSIGNOR TO THEODORE W. FOSTER & BRO. CO., OF PROVIDENCE, RHODE ISLAND.

LIP-STICK HOLDER.

Application filed September 6, 1924. Serial No. 736,227.

To all whom it may concern:

Be it known that I, ARTHUR H. NOBLE, a citizen of the United States, residing at Pawtucket, in the county of Providence and State of Rhode Island, have invented new and useful Improvements in Lip-Stick Holders, of which the following is a specification.

This invention relates to certain new and useful improvements in lip stick holders, and the primary object of the invention is to provide a lip stick holder which has improved means for regularly feeding the lip stick as desired or found necessary.

15 A further object of the invention is to provide feeding means which is positive and reliable in operation and which can be easily operated in addition to being devoid of parts likely to become out of order or deranged.

A still further object of the invention is to provide a holder of light weight, and also feeding means of simple and economical construction, wherein the parts may be easily and quickly assembled.

The invention has still further and other objects which will be later set forth and manifested in the course of the following description.

30 In the drawings:

Figure 1 is a central longitudinal sectional view of the invention.

Figure 2 is a side elevation of the liner in detached position.

35 Figure 3 is a like view of the holder for the lip stick.

Figure 4 is a section on line 4—4 of Figure 1, and

Figure 5 is a section on line 5—5 of Fig. 1.

40 In proceeding in accordance with the present invention a tubular casing 1 is employed on the interior of which a liner 2 of sleeve form is disposed, the latter projecting at its ends beyond the respective ends of the casing 1.

45 A removable closure or cap 3 engages over the outer end of the casing. The inner end portion of the liner is formed with opposed hollow longitudinal keys or ribs 4 that are formed by striking the metal inwardly, while a centrally perforated disk 5 is secured to the bottom of the liner by spinning the metal of the latter over the disk periphery.

50 The lip stick carrier embodies a cup 6 having inwardly struck teeth 7 to grip the

lip stick and a pair of depending legs 8 secured at their upper ends, for example by heading or riveting to the cup bottom. The lower ends of the legs above the bottom 9 have U-shaped guides that slidably receive 60 the ribs or keys 4.

An operating cap 11 engages over the inner end of the liner 2 and has the stem 12 of a screw 14 riveted thereto at 13 whereby rotation of the cap effects rotation of the 65 screw. The screw is engaged with the threads of an aperture provided therefor in the bottom 9 of the carrier while the shank 12 loosely engages in the opening of disk 5 and is guided thereby.

70 From the foregoing it will be seen that rotation of the cap 11 will rotate the screw and the latter in turn will effect sliding of the carrier composed of the parts 6—10 causing the lip stick to be progressively fed outwardly of the liner, the guides 10 and the keys 4 preventing rotation of the carrier and confining its movement to a sliding one.

75 The striking out of the keys or ribs 4, 80 contributes to the light weight of the device also true of the open or skeleton form of carrier 6—10.

Having thus described my invention, what I claim as new and desire to secure by Letters Patent is:

85 1. In a lip stick holder, a tubular casing, a liner sleeve on the interior of the casing having its ends projecting beyond the respective casing ends, said liner having opposed longitudinal inwardly-struck keys, a lip stick carrier including a cup, legs secured to and depending from the cup, a bottom connecting the legs and having a threaded aperture, U-guides connected to 90 the legs and receiving the keys, a rotatable cap on one end of the liner, a perforated disk carried by said end of the liner, and a screw having a shank rigidly connected to 95 said cap and extending through said disk perforation and threaded through said aperture of the bottom of the holder.

100 2. In a lip stick holder, a tubular casing, a liner sleeve on the interior of the casing having opposed longitudinal keys and a 105 perforated bottom, a lip stick carrier having a lip-stick end receiving part, depending legs connected to said part, U-guides on the legs receiving the keys, a connecting part for the legs having a threaded aper-

ture, a screw, and means to rotate the screw, the screw being loosely and guidingly engaged through the perforated bottom of the liner and being threaded through said aperture of the connecting part of the legs.

3. In a lip stick holder, a casing, a tubular member therein having opposite longitudinal keys, a lip stick carrier having depending legs provided with parts which conformably and slidably engage the keys, a member having a threaded opening connect-

ing the legs, a perforated member rigidly connected to the lower end of the tubular member, a screw loosely and guidingly engaged through the perforation of the rigid member and threaded through the opening of the connecting member of the legs, and means to rotate the screw engaged over the rigid member and with the casing.

In testimony whereof I have signed my name to this specification.

ARTHUR H. NOBLE.
